Des. 215,424
Patented Sept. 30, 1969

215,424

DUNE BUGGY BODY

Donald D. Arnett, 4604 Lodge,
Toluca Lake, Calif. 91602

Filed Oct. 22, 1968, Ser. No. 14,107

Term of patent 14 years

Int. Cl. D12—08

U.S. Cl. D14—3

FIG. 1

FIG. 2

FIG. 3

FIG. 4

FIGURE 1 is a perspective view of the dune buggy body, showing my new design;

FIGURE 2 is a side elevational view;

FIGURE 3 is a plan view; and

FIGURE 4 is a front elevational view.

The elements shown in broken lines are included for illustrative purposes only.

I claim:

The ornamental design for a dune buggy body, substantially as shown and described.
